BY Jobaraboy ATTY.

United States Patent Office.

H. D. SMALLEY, OF NEW BALTIMORE, OHIO.

Letters Patent No. 77,544, dated May 5, 1868.

IMPROVEMENT IN PORTABLE FENCE.

The Schedule referred to in these Letters Patent and making part of the same,

TO ALL WHOM IT MAY CONCERN:

Be it known that I, H. D. SMALLEY, of New Baltimore, in the county of Stark, and State of Ohio, have invented new and useful Improvements in Portable Fences; and I do hereby declare that the following is a full, clear, and exact description of my invention, reference being had to the accompanying drawings, forming a part of this specification, and to the letters of reference marked thereon, of which drawings—

Figure 1 is a side view of my improved fence.

Figure 2 is a plan of the same.

Figure 3 is a side view of brace and sill, taken separate from fence-panels.

Figure 4 is a sectional view of fence.

Figures 5 are detail views showing mode of forming corners.

The nature of my invention consists in the peculiar arrangement of fence-panels, brace, and sill in such a manner as that the brace serves both to hold the panels in an upright position, and, at the same time, to bind the two adjacent panels of the fence together, by which means I produce a cheap fence, which can readily be put up or taken down, or from which a panel can easily be taken out, to allow a passage through the fence, and which is very firm and strong, so as to withstand any ordinary pressure from cattle or wind.

To enable others skilled in the art to make and use my invention, I will proceed to describe its construction.

The panels of my fence are made of boards or rails, A, B, C, D, which are secured to the battens, G G, by nails in an ordinary manner. A rail, B; which is next to the top rail, is extended at one end of the panel, as shown at H, the object of which will hereinafter appear.

The sills, E E, are of wood or other suitable material, and have the slots, f, cut in their upper face, of a width equal to the thickness of two panels at the battens, as shown in figs. 2 and 3.

The brace, F, is an ordinary board, of any suitable width, and has the notches d and e cut in it, as seen in fig. 3.

To unite and set up any two panels of my fence, they are set on to the sill E in such a way that the rails A B C D shall come together, and the battens G G be on the outside, and on the sill E, and in notch f.

The brace F is then put in the position shown in fig. 4, and a nail, e, driven through it into the sill E, when the fence is in position and ready for use.

It is readily seen that the brace F, binding over the projection H of the rail B of one panel, and under the next rail above, A, of the other panel, will firmly unite the two panels; and that from the relations sustained by the two panels, brace, and sill, that said panels will be firmly held in an upright position.

When a corner is to be made with this fence, the lower rails, D and D², of the corner panels are extended, and the notches h and k are cut in them, as shown in figs. 5.

The panels are then put into the position shown in figs. 1 and 2, the brace F is put in position shown, and nails a and b are driven through said brace into the rails D and C, when the corner is complete.

A sill, E, is set under the end of one of the corner panels to keep the fence from the ground.

Having thus fully described my improved fence, I do not claim as my invention the panels, sills, or braces taken separately, nor any of the projecting rails, nor any of the notches shown in any of said parts; but

What I do claim as my invention, and desire to secure by Letters Patent, is—

The peculiar arrangement and combination of the panel A² D² with projecting rails D², the panels A D with projecting rail D, and the braces F with notches d and e, the several parts being arranged in the manner and for the purpose specified.

As evidence that I claim the foregoing, I have hereunto set my hand in presence of two witnesses.

H. D. SMALLEY.
